UNITED STATES PATENT OFFICE.

WILLIAM WALTER OWEN, OF ELGIN, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,356,655.

Specification of Letters Patent. Patented Oct. 26, 1920.

Application filed July 30, 1917. Serial No. 183,419.

To all whom it may concern:

Be it known that I, WILLIAM WALTER OWEN, a citizen of the United States of America, and a resident of Elgin, county of Kane, and State of Illinois, have invented certain new and useful Improvements in Measured-Service Telephone Systems, of which the following is a specification.

My invention relates in general to measured service telephone systems and has particular reference to improved measured service equipment for use in operating a subscriber's meter. More specifically my invention relates to an improved method of assessing toll for long distance connections, by automatically operating a subscriber's meter a variable number of times to register the initial charge, and to thereafter operate the meter a variable number of times at predetermined intervals of time, whereby a long distance call may first be automatically charged upon the calling subscriber's meter in accordance with the length of the call and may thereafter be charged upon the meter a variable number of times according to the time consumed in conversation.

The principal object of my invention is an improved timing device which is automatically adjusted during the establishment of the call and which operates at predetermined intervals to operate the meter according to the charge required for the call.

In the drawings I have illustrated one embodiment of my invention in connection with automatic switches of well known type and construction but I do not wish to be restricted to any particular type, my invention being equally adapted to any well known type of system.

Figures 1, 2, 3, and 4 show an established connection from a subscriber in one exchange (Figs. 1 and 2), through a selector and a selector repeater of an intervening exchange (Fig. 3), and through a selector and a connector of a third exchange, to a subscriber in the third exchange (Fig. 4).

Fig. 5 shows a modification of the mechanism to be used with the timing device to avoid the use of relays.

In my prior application Serial No. 167,155 means was provided for automatically charging a long distance call upon a calling subscriber's meter according to the number of exchanges or cities through which that call had progressed. In the present appli-

cation I have shown means for repeating this initial charge at intervals of time after the called man answers.

A register controlling mechanism is provided for each outgoing switch in an exchange, which mechanism is operated one step for each digit which is sent out beyond the first (or calling) exchange, and which is released upon the response of the called subscriber and allowed to transmit a number of impulses of booster battery current to the calling subscriber's meter, the number of impulses sent to the meter being the same or in the proper proportion, to the number of digits sent out by the calling subscriber. 70

The ratio between the digits sent out and the impulses delivered to the meter is determined by the number of digits necessary to call through the exchange and the length of trunk line between exchanges. I have assumed that the trunk lines shown are of equal length, or so nearly equal as to require the same unit of charge, and that each exchange requires three digits, or three operations of the calling device, either to call 80 through an exchange or to call a subscriber in an exchange. It will readily be seen that the trunking can be arranged to meet any further requirement and that, in case more, or less digits are required to call through 85 an exchange, the number of projections on the cam wheels of the impulse sender may be varied accordingly.

My improved timing mechanism is shown diagrammatically in Fig. 2 in connection 90 with the register controlling mechanism R.

My invention may be more clearly understood by reference to the drawings.

The substation A, (Fig. 1) may be of any well known common battery type and comprises the transmitter 2, receiver 3, calling device 4, controlling the impulse springs 5 and 6, and switch hook 7, for controlling the usual switch hook springs to disconnect the ringer 8 and condenser 9 and to connect the transmitter and receiver, in series with the impulse springs, across the line conductors 10 and 11 leading to the exchange. 95

The line switch C in which the line conductors 10 and 11 terminate is similar in all 105 respects to that shown in U. S. Letters Patent No. 1,186,823, granted June 13, 1916, to Frank Newforth, Jr., and comprises among other details a plunger (not shown) attached to the end of a so-called plunger arm 12. 110

which is controlled by the magnet 13, to force into contact, in pairs, a bank of contact springs 14 to 21 inclusive, to thereby extend the line conductors 10 and 11 to a selector switch D.

The master switch G (Fig. 1) is also similar in all respects to that shown in the above mentioned patent and need not be further described here.

10 The selector switch D (Fig. 1) is similar in construction to that shown in U. S. Letters Patent No. 815,321, granted March 13, 1906 to Keith, Erickson and Erickson except that the side switch has been omitted 15 and the circuits have been somewhat modified to adapt it to the modern two-wire system of operation. It comprises among other details a line relay 22, bridge cut-off relay 23, vertical magnet 24, rotary magnet 25, release magnet 27, rotary interrupter relay 26 and a pair of relays 28 and 29, which are slow-acting, that is, slow to deenergize when their energizing circuits are broken, and which control the switching over from one 25 magnet to the other. The vertical magnet 24 and rotary magnet 25, are controlled by the line relay 22 to raise the shaft wipers 30, 31 and 32 and to rotate them into engagement with some pair of contacts similar to 33, 34 and 35.

30 The selector repeater E, (Fig. 2) is similar in construction to that shown in Patent No. 1,312,558, Talbot G. Martin, Aug. 12, 1919, with the addition of the register controlling mechanism R and the timing mechanism X associated with the mechanism R adapted to operate in accordance with my invention, and certain new and useful circuit connections in connection therewith.

40 This selector repeater is provided with 4 wipers, 36-39 inclusive, the wipers 36 and 39 being line wipers adapted to be connected to contacts in the line bank which lead through trunk lines to other exchanges. The 45 wipers 37 and 38 are private wipers for testing purposes. The banks over which these wipers are adapted to rotate have no connection leading to the other exchanges but are connected locally in order to divide the 50 trunk lines leading from the corresponding line contacts into groups and sub-groups; as pointed out in said prior application. This selector repeater comprises among other details the line relay 45, back bridge relay 46, private magnet 47, busy test relay 48, and a 55 number of auxiliary relays, several of which, namely relays 54, 53, 51, 50 and 49, are slow to deenergize when their energizing circuits are broken. The movement of 60 the shaft wipers is controlled through the medium of these relays and their contacts and by means of the vertical magnet 58 and rotary magnet 57, the control of the line relay over said magnets being switched from 65 one to the other by means of the usual side

switch comprising the wipers 71, 72, 73 and 74 controlled by the usual private magnet 47.

Each selector repeater is provided with a register controlling mechanism R comprising a shaft 65, a cam wheel 63, a ratchet wheel 62 associated with the cam wheel 63, a stepping magnet 60 for driving said shaft in a counter clockwise direction, and a release magnet 59, which upon energizing withdraws its armature (which acts as a catch) from the teeth of the ratchet 62, and allows the clock spring to return the shaft and cam wheel to normal position. The cam wheel is loose on the shaft 65 and remains in normal position while the stepping magnet 70 drives the shaft in a counter clockwise direction. However when the shaft is returned by the clock spring, the cam wheel is rotated in a clockwise direction with the shaft by means of the catch or dog 70 thereby bringing the springs 66 and 67 into engagement a number of times according to the number of teeth on the cam wheel. These teeth may be varied in number according to requirement as hereinbefore pointed out. The stepping magnet 60 of the mechanism is controlled by the slow-acting relay 53, which relay is operated only once for each set of impulses transmitted over the trunk line leading to the next exchange. 95 The slow-acting relay 54 is used for discriminating purposes and is energized only when an incoming selector seizes the line to the selector repeater as will be pointed out. An additional relay 51 is also provided to 100 release the register controlling mechanism R and prevent it from delivering impulses to a subscriber's meter in case a call is set up and the called subscriber fails to respond.

105 The improved timing mechanism X comprises a number of relays 301-304 inclusive, which are controlled by a wiper 300 attached to the shaft 65 and a dial or impulse sender having a wiper 305 which is rotated step by step over a number of contacts to 110 send impulses of booster battery to the release trunk. A rotary mechanism is provided for stepping the wiper 305 and comprises a ratchet wheel 306 which is operated by a stepping magnet 307 and a release magnet 308 for allowing the ratchet 306 and the wiper 305 to return to normal. As the ratchet 62 of the mechanism R is rotated the wiper 300 which is attached to the shaft 65 also rotates and successively 115 connects with contacts leading to the relays 301 etc. As soon as a call is completed and the wiper 301 is left standing on one of said contacts, the release magnet 59 of mechanism R is energized to release the ratchet 62 120 and shaft 65. The wiper 300 also returns to normal but the relay with which said wiper was connected remains in energized position over a circuit closed by its own lower armature and through a contact 309 130

which is closed by the magnet 59 before the armature leaves the teeth of ratchet 62. Another circuit is also closed by magnet 59 extending from ground through contact 309 5 to the stepping magnet 307 through a pair of springs 311 which are controlled by a clock to close every minute or certain period of time so that the wiper 305 will be rotated one step for each period of time as 10 long as the magnet 59 remains energized or until conversation is completed. It will be understood that the contacts over which the wiper 305 rotates may be varied in number according to requirements, that is, any number 15 of these contacts may be passed over in any stated time so that a subscriber may be charged only a certain percentage of initial charge for each interval after the first or initially charged interval. As I have shown 20 in the drawings, assuming that three minutes elapses before the wiper reaches contact 312, then for each three minutes thereafter the subscriber may be charged either one, two, three or four times, depending 25 upon which of the relays 301 etc. have been energized. When the magnet 59 deenergizes at the completion of conversation the circuits of the locked relay and of magnet 307 are opened at contact 309 and a circuit 30 is closed for the release magnet 308 which energizes and thereby returns the timing mechanism to normal.

The selector D' (Fig. 3) is similar to the selector D (Fig. 1), with the exception of 35 the magnet 75 which is legged off from the release trunk to battery. This selector is accessible only to incoming calls from selector repeaters in another exchange. The magnet 75 is for the purpose of energizing 40 the relays, similar to 84, in the selector repeater with which this incoming selector connects, when the call originates in another exchange.

The selector repeater E' (Fig. 3) is similar 45 in all respects to the selector repeater E (Fig. 2).

The selector D² (Fig. 3) is another incoming selector of the third exchange similar 50 to the selector D' (Fig. 3). The connector switch F (Fig. 4) is similar 55 in all respects to the connector shown in the before mentioned Letters Patent No. 1,186,823 and is of the booster battery type, that is, when the called man answers, an impulse 60 of current from the booster battery B' is transmitted back over the release trunk to the calling subscriber's meter. This impulse of booster current is effective only in case a call is local to one exchange. The back bridge of this connector switch also 65 reverses the battery in the trunk line leading back toward the calling line and this reversal is effective when a call is received from another exchange, to release the register controlling mechanism of the selector re-

peater in the originating exchange. The connector F comprises among other details the line relay 134, which is bridged across the line conductors through the springs of the back bridge relay 133, the release relay 70 135, busy relay 136, series relay 137, ring cut-off relay 138, ringing relay 139, wiper cut-off relay 140, additional back bridge relay 132, and auxiliary relay 276, these relays control the vertical magnet 142, and 75 rotary magnet 141, to step the wipers 146, 147, and 148 into engagement with a desired line.

The substation A' and line switch C' are 80 in all respects similar to the substation A and the line switch C.

Having given a general description of the apparatus involved I will now explain in detail how a subscriber at substation A may obtain connection with the subscriber 85 at substation A' and how the proper charge may be assessed upon the meter of the calling subscriber. We will assume for the purpose of this explanation that three digits are required to call through each exchange 90 shown, one for each selector and two for each selector-repeater and connector. The subscriber at A must therefore send three digits to call out of his own exchange, three to call through the intervening exchange, 95 and three to call a subscriber in the third exchange. It will be understood that this arrangement is only arbitrary and may be varied at will to suit existing conditions.

Upon the removal of the receiver at the 100 substation A from the switch-hook, the talking circuit of the substation is bridged across the line conductors 10 and 11 by the hook switch springs, thereby closing the circuit of the line relay 149 of the line switch 105 C. This circuit extends from ground G' through springs 150 and 151, line 11, substation A, line 10, springs 152 and 153, and line relay 149 to battery B. Relay 149, upon energizing, closes the circuit of the operating winding 154, which energizes and disconnects the relay 149 from the line and thrusts the plunger into the terminals of the trunk before which it is held by the master switch. The springs 14 and 18 and 110 17 and 21 being pressed together, extend the connection to the selector switch D, and close an energizing circuit for the line relay 22 thereof which circuit extends from ground G' through the lower winding of 115 relay 22, springs 166 and 165, springs 21 and 17, to and through the substation A and back through springs 14 and 18, 157 and 156, and upper winding of relay 22 to battery B'. The line relay, upon energizing, closes a circuit from ground G' 120 through springs 168 and 167, to the relay 28 and battery B'. The relay 28, upon energizing, supplies a holding ground for the winding 155 of the line switch C from 125 130

ground G^5 to hold the plunger in engagement with the bank springs after the relay 149 has fallen back. Although a branch of the circuit extending to winding 155 also 5 extends through the meter J to battery, the meter is not operatively energized, the winding thereof being of comparatively high resistance and the armature being adjusted so as not to operate by current from 10 the battery B. The meter J is somewhat different from the meter shown in said Letters Patent, in that, it will not hold up after it has been once operated, but will deenergize after each impulse of booster battery. 15 The preliminary non-numerical operations being completed, the line relay 22 is now operated in accordance with the first digit of the called number to operate the vertical magnet 24 to step the wipers 30, 31 and 32 20 to some level of the banks, from the contacts of which, trunk lines lead to selector repeaters which have access to outgoing trunk lines. As soon as the desired level is reached and the impulses cease, the rotary 25 magnet 25 is operated to rotate the wipers into engagement with an idle one of said trunk lines, which we will assume leads to the selector repeater E (Fig. 2). As soon as this idle trunk line is found the bridge 30 cut-off relay 23, which, during the rotation over busy trunk lines has been short circuited by the ground on the private contacts, energizes over the following circuit: ground G^5 , armature 170 and its front contact, relay 23, interrupter springs 171 of the 35 rotary magnet, off-normal springs 172, and through relay 26 to battery B^4 , the relay 26 is of a lower resistance than relay 23, and does not energize over this circuit. The 40 relay 23 however, energizes and disconnects the relays of the switch D from the line conductors and extends the line conductors 10 and 11 through the wipers 30 and 33 and 31 and 35 to the line relay 45 of the selector repeater. 45

The line relay 45 of selector-repeater E (Fig. 2) energizes over the following circuit: ground G^6 , lower winding of relay 45, springs 178 and 176 of relay 46, contact 45, wiper 31, springs 164 and 165, 50 springs 21 and 17, line conductor 11, substation A, line conductor 10, springs 14 and 18, springs 157 and 158, wiper 30, contact 33, springs 175 and 173, and through the upper winding of relays 45 to battery B^6 . Relay 45 upon energizing over this circuit, closes a circuit from ground G^7 through springs 180 and 181 and relay 50 to battery B^7 . The relay 50, upon energizing, supplies a holding ground for the relay 23 of selector D over the following circuit: ground G^8 , springs 186, through the low resistance relay 54, contact 34, wiper 32, springs 160 and 161, relay 23, springs 171, off-normal springs 172, and relay 26 to battery B^4 .

The relays 26 and 54 do not energize over this circuit in series with the high resistance relay 23. The relay 23 is however held in its operated position to maintain the connection through to the selector repeater 70

The subscriber at the calling substation now operates his calling device for the second digit, thereby momentarily interrupting the circuit of the line relay 45 of the selector repeater E a number of times, depending upon the level of the bank in which the trunk with which he desires to connect is located. The relay 50 is slow acting and retains its armatures in operated position during the energization and deenergization 80 of the line relay. Each time the line relay 45 deenergizes, a circuit is closed from ground G^7 through the springs 180 and 179, springs 189 and 190, relay 49, vertical magnet 58, and side switch wiper 71 (in first 85 position) to battery B^8 . The impulses transmitted through the vertical magnet cause said magnet to raise the wipers to a position opposite the desired level of bank contacts, the first sub-group of which level 90 we will assume is connected to incoming selectors in the third exchange similar to selector D¹ (Fig. 3). The relay 49, which is included in this circuit in series with the vertical magnet is a slow acting relay and remains 95 energized during the entire time the vertical magnet is operating. In its energized position the relay 49 completes a circuit from ground G^9 through springs 191 and 193 and private magnet 47 to battery B^{11} . 100 When the relay 49 deenergizes after the last impulse is delivered to the vertical magnet, it breaks the circuit of the private magnet 47, which thereupon deenergizes and allows the side switch to pass from first to second 105 position. The side switch wiper 71, in passing from first to second position, transfers the battery connection from the vertical magnet 58 to the rotary magnet 57. Therefore when the calling subscriber operates 110 his calling device for the next or third digit the operation of the line relay 45 transmits a series of impulses through the rotary magnet to rotate the wipers 36, 37, 38 and 39 onto the first trunk line of the first group 115 which in this case leads to the selector D¹ (Fig. 3). After the impulses for this digit cease the relay 49 again deenergizes and allows the side switch to pass from second to third position, that is, assuming this trunk 120 line to be idle. If this trunk line had been busy however the wiper 37 would have found the contact with which it engaged provided with a guarding ground potential. This guarding potential would have provided an energizing circuit for the relay 55, 125 extending from wiper 37, side switch wiper 73 (in second position), and relay 55 to battery B^9 . The relay 55, upon energizing, completes a circuit from ground G^{10} 130

through springs 194 and the private magnet 47 to battery B¹¹. This circuit maintains the private magnet energized after the relay 49 is deenergized and therefore holds the side switch in second position. The deenergization of the relay 49 after this set of impulses closes a new circuit for the rotary magnet from ground G⁶, springs 191 and 192, springs 196 of relay 55, springs 198, 10 springs 200 of relay 48, rotary magnet 57, and side switch wiper 71 to battery B⁸. The rotary magnet will energize over this circuit to step the shaft wipers to the next trunk line, and also closes a circuit from 15 ground G¹¹ through springs 202 and relay 56 to battery B¹¹. The relay 56, upon energizing, interrupts the circuit of the rotary magnet at the springs 198. The rotary magnet in turn deenergizes and breaks the 20 circuit of the relay 56, which in turn deenergizes and again closes the circuit of the rotary magnet. The relay 55 will remain energized as long as the wiper 37 continues to engage grounded contacts of busy trunk 25 lines, and the rotary magnet will continue to advance the wipers step-by-step until a non-grounded contact is found, which will permit the relay 55 to deenergize, or until the wipers 37 and 38 engage a pair of contacts which are connected together. The 30 last trunk line of each subgroup has a pair of contacts similar to 42 and 43, which are connected together and the selector repeater upon being advanced to this last trunk line 35 will come to rest whether the line associated therewith is idle or busy and if busy the side switch is locked in second position and a busy tone given to the calling subscriber in the manner pointed out in said prior application No. 655,985.

When the wipers of the selector repeater come to rest upon the contacts of an idle trunk line and the side switch passes to third position as has been explained, the 40 connection is completed with the trunk conductors 203 and 204 by the closure of the back contacts 205 and 206 of the private magnet. The side switch wiper 73 upon passing to third position extends a guarding potential from ground G¹² through the wiper 73 and the private wiper 37 to the private bank contact of the seized trunk line in the banks of all switches which have access thereto. The side switch wiper 74, upon 45 reaching third position, completes a bridge across the trunk conductors 203 and 204, whereupon the line relay 77 of the selector D' (Fig. 3) becomes energized over a circuit from ground G¹³, through the lower winding of relay 77, springs 215 and 214, conductor 204, contact 44, wiper 39, side switch wiper 74, impedance coil 216, lower winding of back bridge relay 46, springs 182 of line relay 45, wiper 36, contact 41, 50 conductor 203, springs 208 and 207, and upper winding of relay 77 to battery B¹⁰. The line relay 77 energizes over this circuit and closes the circuit of relay 78. The relay 46 of the selector repeater E, one winding of which was included in the above traced 55 circuit, does not energize at this time, the current flow in the lower winding being in the opposite direction to that flowing in the upper winding. The circuit for the upper winding of said relay may be traced from ground G¹⁴ through springs 217 (which were closed on the first vertical step of the switch E) and through the upper winding of relay 46 to battery B¹⁶. The relay 46 requires the energization of both windings 60 in the same direction in order to operatively energize.

When the substation calling device is operated for the fourth digit the circuit of the line relay 45 of the selector repeater E 65 is again interrupted momentarily a number of times. The separation of the springs 182 at this time, opens the bridge across the trunk conductors 203 and 204, thereby breaking the circuit of the line relay 77 of selector D'. The line relay 77 in response to the opening and closing of this bridge operates in the same manner as the line relay 22 of selector D (Fig. 1) to control the vertical and rotary magnets 82 and 83, to 70 pick out an idle trunk. Each time the line relay 45 of the selector repeater E deenergizes to repeat an impulse to the line relay of the connector, a circuit is closed from ground G¹ through springs 180 and 179, 75 springs 189 and 190, relay 49, relay 53, and side switch wiper 71 to battery B⁸. The operation of relay 49 is functionless and simply causes the private magnet to open the 80 trunk conductors leading back to the condensers while impulses are being repeated. The relay 53, being slow-acting, remains in its energized position during the entire time the relay 45 is operating in response to a digit. This operation of the relay 53 accomplishes a double result, namely, the 85 short circuiting of the resistance 216 and one winding of relay 46 to remove their resistance from the circuit of the line relay 77 of selector D', and the operation of the stepping magnet 60 of the register controlling mechanism R. The circuit for the magnet 60 may be traced from ground G¹⁵ through springs 218, springs 220 and magnet 60 to battery B¹⁵. The magnet 60, upon 90 energizing, attracts its armature and steps the ratchet wheel 62 one step in a counter clockwise direction. As pointed out hereinbefore the cam wheel 63 does not move at this time, but the ratchet wheel 62, being 95 rigid on the shaft, rotates together with the shaft and the wiper 300 and stores up tension in the clock spring 222. After the impulses for this digit cease, the circuit of the 100 relay 53 is broken at contacts 180 and 179 105

of the line relay, and upon deenergizing, allows the magnet 60 to deenergize in turn. The ratchet wheel 62 is held in operated position by means of the armature of the 5 release relay 59 which engages the teeth of ratchet wheel 62.

Returning to the operation of selector D' (Fig. 3), as soon as an idle trunk line in the level leading to the selector repeaters of 10 this second exchange has been seized, the relay 76 is energized in the same manner as the relay 23 of selector D, and operates to disconnect the operating relays of the selector from the trunk lines 203 and 204 and to connect 15 said trunk lines through the wipers 102 and 103 to the selector repeater E'. A circuit is thereby closed for the line relay 87 of the selector repeater E' extending from ground G¹⁶ through the lower winding of 20 said relay springs 223 and 224, contact 107, wiper 103, springs 213 and 214, and over the previously traced circuit through the bridge across the conductors 203 and 204 and back over the other side of the line through 25 springs 208 and 209, wiper 102, contact 105, springs 225 and 226, and upper winding of relay 87 to battery B²⁴. The line relay 87, upon energizing, closes a circuit for the relay 90, which in turn energizes and supplies 30 a holding ground for the relay 76 of the selector D', which extends from ground G¹⁸ through springs 230, relay 84, over the private conductor to contact 106, wiper 104, springs 211 and 212, and through the relays 35 76 and 80 to battery B²¹. A branch of the above traced circuit extends from the spring 212 through the relay 75 to battery B¹⁷. It will be seen that this circuit differs somewhat from the holding circuit of the relay 40 23 of selector D in that the relay 75 is connected in multiple with the relays 76 and 80. All of the incoming selectors of each exchange which are accessible to incoming calls only are equipped with a relay similar 45 to the relay 75, the purpose of which is to so increase the current flowing in the circuit through the relay 84, or similar relays, as to allow said relay 84 to operatively energize to disconnect the register controlling 50 mechanism R' from the controlling relays of the selector repeater E'. The relay 84 will therefore energize over the above traced circuit and will maintain the circuit of the stepping magnet 232 of the controlling 55 mechanism open at the springs 234, and the circuit of the release magnet 233 open at the springs 235.

When the substation calling device is operated for the fifth digit, the circuit of the 60 line relay 45 of the selector repeater E is again interrupted a number of times. The separation of the springs 182 and the resulting interruption of the bridge across the conductors 203 and 204, in this case opens 65 the circuit of the line relay 87 of the selec-

tor repeater E' a corresponding number of times, to in turn control the vertical magnet 96 in the same manner as set forth in connection with the line relay 45 of switch E. The slow-acting relay 53 of the selector repeater E is again energized once in response to the operation of the line relay 45 over the previously traced circuit and again closes the circuit of the stepping magnet 60 of the register controlling mechanism R. The 70 ratchet wheel 62 is thereupon given a second step and the relays 53 and magnet 60 again deenergize upon the cessation of the impulses through the line relay. The 75

When the substation calling device is operated for the next digit, the circuit of the line relay 45 of the selector repeater E is again broken a number of times and again operates to repeat a corresponding number of impulses to the line relay 87 of selector repeater E' (Fig. 3), and to step the ratchet wheel one more step through the medium of the relay 53. The line relay 87, in response to the impulses of this series, operates to control the circuit of the rotary magnet 97 to rotate the wipers 108, 109, 110 and 112 onto the terminals of an idle trunk line in the desired subgroup, the trunk lines of which lead to a third exchange and which terminate in selector switches D² (Fig. 4). The 80 As soon as the wipers come to rest on the contacts 113, 114, 115 and 117, a circuit is closed for the line relay 120 of the selector D² as follows, from ground G¹⁹ through the lower winding of the line relay 120, springs 100 246 and 245, contact 117, wiper 112, side switch wiper 101, resistance 247, lower winding of back bridge relay 86, springs 248, wiper 108, contact 113, springs 237 and 236, and upper winding of relay 120 to battery B²⁴. The back bridge relay 86 of the selector repeater E' being similar to the relay 46 of switch E does not operatively energize over the above traced circuit, the current in the lower winding being in opposition to that flowing in the upper winding. The line relay 120, however, energizes over this circuit and closes a circuit for the relay 250, which energizes to prepare the circuit of the vertical magnet. The 110

When the substation calling device is operated for the next digit of the called number, the circuit of the line relay 45 is again opened a number of times and again operates to transmit a corresponding number of 120 impulses to the line relay 87 of selector repeater E' (Fig. 3). The side switch of the selector repeater E' being in third position at this time, each time the line relay 87 deenergizes the circuit of the line relay 120 of the selector D² (Fig. 4) is broken at the springs 248 in the same manner in which the line relay 77 of selector D' was controlled by the line relay 45 of selector repeater E. It will thus be seen that the impulses for 125 134

this and the following digits are relayed or repeated twice, first by the line relay 45, and again by the line relay 87. The line relay 120 operates in response to this digit, to 5 raise the wipers 126, 127 and 128 to some level of the banks from which trunk lines lead to connectors similar to connector F. As soon as the impulses cease, the rotary magnet 125 is brought into operation in the 10 usual manner to rotate the wipers to the contacts of an idle trunk line, in this case the contacts 129, 130 and 131. Referring again to the selector repeater E, the relay 53 again energizes during the operation of 15 relay 45 and closes the circuit of stepping magnet 60, whereby the ratchet wheel 62 is given a fourth step. Although the slow-acting relay 85 of selector repeater E' is also energized at this time by the relay 87, the 20 stepping magnet 232 is not energized, due to its circuit being held open at the springs 234 of relay 84 as previously explained. It will be understood that the selector repeater E' is also supplied with a timing mechanism 25 (not shown) similar to X (Fig. 2).

As soon as the wipers 126, 127 and 128 come to rest on the contacts 129, 130 and 131, the relay 119 is energized and operates to extend the connection through the wipers 30 126 and 127 to the line relay 134 of connector F. The circuit for relay 134 extends from ground G²¹ through the lower winding of relay 134, springs 251 and 252, contact 130, wiper 127, springs 244 and 245, and 35 over the previously traced circuit through the lower winding of the back bridge relay 86 of selector repeater E' and springs 248 and back over the other side of the trunk through the springs 237 and 238, wiper 126, 40 contact 129, springs 255 and 254, and upper winding of relay 134 to battery B³⁰. The relay 86 for reasons stated before does not energize over this circuit, the line relay 134, however energizes and closes a circuit from 45 ground G²¹, springs 257 and 258 and relay 135 to battery B³⁰; the relay 135 in turn energizes and supplies a holding ground for the bridge cut-off relay 119 of the selector D'. The circuit for the relay 119 extends 50 from ground G²² through springs 261 and 262, springs 263 and 264, contact 131, wiper 128, springs 240 and 241, and through the relays 119 and 122 in multiple with the relay 118 to battery B³⁰.

55 When the substation calling device is operated for the next digit, the circuit of the line relay 45 of selector repeater E is again broken a number of times, and repeats the impulses to the line relay 87 of selector repeater E', which in this case, by the separation of the springs 248 repeats a corresponding number of impulses to the line relay 134 of the connector F over the previously traced circuit. The operation of the relay 53 of the selector repeater E again closes the

circuit of stepping magnet 60, whereby the ratchet wheel 62 is given a fifth step. The relay 135 of connector F being slow-acting, the operation of the line relay 134 controls the circuit of the vertical magnet 142 to 70 raise the wipers 146, 147, and 148 to the level of the bank in which the conductors of the desired line terminate, in the well known manner and as pointed out in the above mentioned Letters Patent No. 75 1,186,823. The slow-acting relay 137 which is included in the circuit of the vertical magnet, deenergizes, when the impulses for this digit cease, and substitutes the rotary magnet 141 for the vertical magnet 142, to the 80 control of the line relay 134 by means of the side switch.

When the substation device is operated for the last digit the circuit of the line relay 45 is again broken a number of times, the 85 magnet 60 is also operated to give the ratchet wheel 62 a sixth and last step, and the impulses are repeated over the previously traced circuits to the line relay 134 of connector F. The line relay 134 operates 90 in response to this series of impulses to deliver a corresponding number of impulses to the rotary magnet 141 whereby the wipers are rotated to the contacts of the desired line. Assuming the called line to be idle 95 the side switch now passes to the third position and the ringing relay 139 is intermittently operated to disconnect the calling line from the called line and to apply ringing current from the generator H to the terminals of the called line. The side switch wiper 265 on passing from second to third position establishes a guarding potential on the private contacts of the called line and closes an energizing circuit for the cut-off 100 winding 145 of the called subscriber's individual switch C', whereby the line and operating magnets are disconnected from the line conductors.

When the called subscriber removes his 110 receiver from the switch hook, in response to this signal, or as soon as the ringing relay 139 deenergizes, if it is energized at the time, a circuit is closed from ground G²³ through the relay 133, springs 266, springs 115 268, wiper 148, to and through the substation A' and back over the other side of the line through the wiper 146, springs 270, springs 272, and through the relay 132 to battery B³⁰. The relay 133, upon energizing, 120 reverses the connections of the line relay 134 to the trunk conductors, and thereby reverses direction of the current flow in the trunk. The relay 132, upon energizing, closes a circuit from ground G²⁴ through the off-normal springs 274, springs 275, relay 276, and through the ring cut-off relay 138 to battery B⁴⁰. The relays 276 and 138 energize over this circuit, and the relay 138, upon energizing, opens the circuit of the 125 130

ringing relay 139 and locks itself to ground G²⁴ by means of the springs 277. When the springs 277 engage it will be seen that the relay 276 is short circuited and immediately deenergizes. This momentary energization of relay 276 connects the battery B¹⁴ in series with the release trunk. This battery has the negative pole grounded instead of the positive pole as the other battery and therefore a booster impulse is transmitted over the release trunk. This booster impulse is effective in local calls in one exchange and is used to operate a meter as explained in the before mentioned patent.

15 Of course in the call which I have illustrated this booster impulse will be functionless as the release trunk does not extend to a meter. The reversal of current in the trunk by the relay 133 energizes the back bridge relay 86 of the selector repeater E' (Fig. 3), the current in both upper and lower windings now assisting each other. The relay 86 upon energizing in turn reverses the battery to the trunk line 203 and 204 leading to

20 the selector repeater E (Fig. 2). This reversal of current causes the back bridge relay 46 of the selector repeater E to operatively energize, to reverse the battery in the trunk toward the calling man and to also close the contact of springs 184 whereby a circuit is closed for the release magnet 59 of the register controlling mechanism as follows: from ground G²⁵ through springs 184, springs 277, and magnet 59 to battery B¹⁴.

25 The magnet 59 upon energizing withdraws its armature from the teeth of the ratchet wheel 62 and allows the clock spring 222 to rotate the ratchet wheel 62 in a clockwise direction to its normal position. The cam wheel 63 will now be rotated with the ratchet wheel by means of the dog 70 to close the springs 66 and 67 a number of times. The springs 66 and 67 will be operated the same number of times that the

30 magnet 60 was operated in the progress of the call. The operation of the springs 66 and 67 closes a circuit from booster battery B¹² through resistance 280, springs 66 and 67, springs 282, contact 34, wiper 32, springs 160 and 161, springs 19 and 15 and through the meter J to battery B. The battery B¹² being connected in series with the battery B through the meter J, the meter will energize each time the springs 66 and 67 close. It

35 will be seen therefore that the meter J will be operated a number of times corresponding to the number of digits which have been repeated over the trunk line to another exchange and in this case the subscriber's meter is operated six times or three times for each exchange through which the call has progressed. As the ratchet wheel 62 was operated six steps during the operation of the call, it will be seen that the wiper 300

40 was also operated six steps and rests on the

contact 318 which is connected to relay 303. The relay 303 therefore energizes over a circuit from ground G⁸⁰ through wiper 300, contact 318, and relay 303 to battery B⁵⁰, and attracts its armatures 319 and 320. The 70 armature 319 upon pulling up prepares a circuit from the contacts 312, 313, 314 and 315, 316, and 317 to the release trunk and thence to the meter J. The armature 320 prepares a locking circuit for the magnet 75 303. When the release magnet 59 is now energized by the response of the called subscriber the locking circuit for relay 303 is completed at contact 309 from ground G⁸¹ and a circuit is also closed for the stepping 80 magnet 307 through the clock controlled contacts 311. The magnet 307 therefore operates once each time, the springs 311 are closed to step the wiper 305 one step. As the meter has already been operated by the cam 85 wheel 63 for an initial charge, the subscriber is entitled to a three minute conversation without further charge, but should the conversation last for more than three minutes the wiper 305 will then pass onto the contact 90 312 and a booster impulse from the battery B⁵¹ will be supplied to the meter J. As previously pointed out, the springs 311 of the timing device X are controlled by a clock and the wiper 305 is on the same shaft with 95 the ratchet wheel 306, so that each time the springs 311 close the wiper 305 takes one step. The contacts engaged by the wiper 305 may be connected in any desired manner, but as shown, and supposing that the 100 wiper 305 meets the contact 312 at the end of the first three minutes of conversation then each time 305 meets a contact 312, 313, 314, etc., a booster impulse will be sent from the battery B⁵¹ to the meter. The circuit 105 over which this impulse passes extends from booster battery B⁵¹ through resistance 322, wiper 305, contact 312, armature 319, springs 282, and over the previously traced circuit to the meter J. It will be seen therefore that the meter will be operated three times for each three minutes after the first three. If the call had extended through more or less exchanges it will be seen that the meter would be operated either more or less times according to which relay was last energized by the wiper 300.

110 After conversation is completed the connection is released by the restoration of the receiver at the calling station in a manner well known and which is fully described in the publication herein referred to. When the release magnet 59 of the register controlling mechanism is released upon the release of the switch E, the locking circuit of 115 the relay 303 is opened and the relay deenergized to disconnect the timing mechanism from the release trunk. The circuit of the release magnet 308 is also closed by the deenergization of magnet 59 and extends 120

125 130

from ground G^{31} through contact 310, off-normal springs 321, and magnet 308 to battery B^{32} . The magnet 308 upon energizing, removes its armature from the teeth of the ratchet 306 and allows said ratchet to be returned with the wiper 305 to its normal position by spring tension. The circuit of magnet 308 is opened at the off-normal springs 321 when the mechanism reaches 10 normal position.

Let us suppose that a calling subscriber has called a party who fails to answer and the switches are released. As the registering mechanism R has been operated a number of steps during this call some means must be provided for preventing any false operation of the meter J under these circumstances. The slow-acting relay 51 has been added to the selector repeater E (Fig. 2) 15 to overcome this difficulty. When the uncompleted connection is released, the release magnet 52 of the selector repeater E is energized and in turn closes a circuit for the relay 51 from ground G^{24} through the springs 283 and relay 51 to battery B^7 . The relay 51, upon energizing closes a circuit for the release magnet 59 by means of the springs 285, and also opens the circuit which leads from the springs 66 and 67 to the 20 release trunk. The register controlling mechanism will therefore be returned to normal position without sending any impulses of booster current to the subscriber's meter.

When a line is busy either by reason of 25 having made a call or by reason of having been called, the busy relay 136 is energized in the usual manner and the calling subscriber is given a busy signal, whereupon the connection is released in the usual manner. Although I have shown a plurality of 30 batteries throughout the drawings, it will be understood that only one battery may be used for each exchange.

In Fig. 5 I have shown another method of 35 accomplishing the same result which is accomplished by the wiper 300 and the relays 301, 302 etc., (Fig. 2). In this modification I show a plurality of wipers 404 on the shaft 65' which are loose on the shaft and 40 are mounted thereon as a unit together with the ratchet wheel 400. Firmly attached to the shaft 65' is an arm 401 which extends beyond all of the wipers 400 so that when the shaft is rotated, the arm 401 rotates 45 the wipers with it and when the shaft is later released, the wipers will remain in their advanced position in contact with a certain row of bank contacts. The wipers 404 are all connected together and 50 a conductor extends therefrom to the release trunk through the springs 282 in Fig. 2. The first contacts in the 2nd, 4th, 6th and 8th rows are connected to the contacts 312, 315, etc., over which the wiper 305 55 (Fig. 2) rotates, the second contacts in the

4th, 6th and 8th rows are connected to the contacts 313, 316, etc., the third contacts in the 6th and 8th rows are connected to the contacts 314, 317 etc., and the fourth contact in the 8th row may be connected to the 70 fourth contact on the said dial when such is required. It will therefore be seen that when the shaft 65' is stepped six steps in the progress of a call, the wipers 404 will be rotated onto the sixth set of contacts, so that 75 when the called subscriber answers and the wiper 305 rotates, the impulses from battery B^{51} will pass through the contacts 312, 313, and 314 and through the contacts of the 6th row and the wipers 404 which rest thereon 80 to the release trunk. When the conversation is completed, the magnet 402 is energized at the same time that the release magnet 308 (Fig. 2) is energized and removes the ratchet 403 from the ratchet wheel to 85 allow the wipers 404 to return to normal.

It will be seen therefore that I have provided a very efficient method of automatically registering long distance calls, and of automatically charging upon the calling subscriber's meter an additional charge for additional time after the first or free period, and that the method of accomplishing this result is very flexible and may be varied in 90 a number of ways by one skilled in the art 95 to adapt it to any conditions. Although I have illustrated and explained my invention in connection with a particular type of automatic switches, it is of course understood that I do not wish to be limited to the 100 exact construction shown and described, but my invention is capable of use with any other well known system.

What I claim as my invention is:

1. In a telephone system, calling and 105 called subscribers' lines, a registering device for each line, means for extending a calling line into connection with called lines through a plurality of exchanges, means for operating said device in accordance with the number of exchanges through 110 which the connection is extended, a time controlled mechanism, said device also controlled by said mechanism in accordance with the number of exchanges. 115

2. In a telephone system, a calling line, 120 called lines having different toll rates, a meter for the calling line, means for extending a connection from said calling line to one of said called lines over a plurality of successive link circuits, a timing device for controlling said meter, means for automatically adjusting said device according to the 125 number of link circuits over which the connection is extended, and means controlled by the called subscriber for controlling said device to operate said meter at predetermined intervals during conversation according to the toll rate of the called line.

3. In a telephone system, a calling line, 130

- called lines having different toll rates, a meter for the calling line, means for extending a connection from said calling line to one of said called lines, a timing device for controlling said meter, means for automatically adjusting said device according to the toll rate of the called line, and means controlled by the called subscriber for controlling said device to operate said meter at predetermined intervals during conversation.
4. In a telephone system, a meter, a timing device for controlling the operation of said meter, said device comprising a movable wiper, means for driving said wiper, a plurality of contacts over which said wiper passes, means for connecting any number of said contacts with said meter, and a circuit for said meter which is closed by the connection of said wiper with said connected contacts to thereby operate said meter.
5. In a telephone system, a plurality of exchanges, subscribers' lines in each exchange, means for extending a connection from a line in one exchange to a line in any other exchange through any number of intervening exchanges, a meter for the calling line, means controlled by the called subscriber for operating said meter in accordance with the number of intervening exchanges, and a timing device for thereafter automatically operating said meter a plurality of times for each time interval during which said lines remain connected.
6. In a telephone system, a calling and a called subscriber's line, means for extending a connection between said lines through a plurality of exchanges, a meter for the calling line, a circuit for said meter, means for closing said circuit a plurality of times upon the response of the called subscriber to operate said meter according to the number of exchanges through which the call is extended, and automatic means for thereafter closing said circuit a plurality of times at regular intervals to again operate said meter.
7. In a telephone system, calling and called subscribers' lines, automatic switches for connecting any two of said lines for conversation, means for controlling said switches by a plurality of series of impulses to establish said connection, a register for the calling line, means for operating said register upon the response of the called subscriber, a timing device associated with one of said switches, and means controlled by said device for thereafter operating said register a variable number of times depending upon the number of series of impulses used to control said switches.
8. In a telephone system, calling and called subscribers' lines, automatic switches for connecting any two of said lines for con-
- versation, means for controlling said switches by a plurality of series of impulses to establish said connection, a register for the calling line, means for operating said register upon the response of the called subscriber, a timing device associated with one of said switches, said device adjusted by said one switch during the establishment of said connection, and means controlled by said device for thereafter operating said register a variable number of times depending upon the number of series of impulses used to control said switches.
9. In a telephone system, calling and called subscribers' lines, automatic switches for connecting any two of said lines for conversation, means for controlling said switches by a plurality of series of impulses to establish said connection, a register for the calling line, means for operating said register upon the response of the called subscriber, a timing device associated with one of said switches, said device adapted to be adjusted according to the number of impulses used to operate said switches.
10. In a telephone system, calling and called lines, a register for each line, automatic switches for establishing a connection between a calling and a called one of said lines, means for sending a plurality of series of impulses to said switches to establish said connection, means for charging for said connection by operating the calling subscriber's meter once for each series of impulses sent, and means for thereafter repeating said charge at predetermined intervals.
11. In a telephone system, subscribers' lines, means for establishing connections between said lines over a plurality of serially related trunk lines, a timing device, and means for automatically adjusting said device according to the number of trunk lines in the connection established to register the charge for the same.
12. In a telephone system, calling and called lines, trunk lines each requiring a toll charge, means for extending connections between said lines over one or more of said trunk lines, means for automatically charging the calling subscriber according to the number of trunk lines over which the call is extended, and means for automatically repeating said charge at predetermined intervals.
13. In a telephone system, calling and called lines, trunk lines each requiring a toll charge, means for extending connections between said lines over one or more of said trunk lines, means for automatically charging the calling subscriber according to the accumulated charge required for the trunk lines used in the connection, and means for automatically repeating said charge at predetermined intervals.
14. In a telephone system, calling and

- called lines, trunk lines each requiring a toll charge, means for extending connections between said lines over one or more of said trunk lines, a timing device, and means controlled by said timing device for automatically charging the connection to the calling subscriber according to the number of trunk lines over which the call is extended.
15. In a telephone system, in which means are provided for setting up connections automatically between calling and called lines, each line having a meter, and in which the calls so set up require varying toll charges, a common mechanism controlled by the response of the called subscriber for operating the meter a varying number of times in accordance with the charge required, and a timing device operable to assess a charge upon the calling subscriber's meter at predetermined intervals during conversation, said timing device adjusted during the establishment of a call to assess a toll in a certain proportion to the initial charge.
16. In a telephone system in which means are provided for setting up connections through a plurality of intervening exchanges from calling to called lines, and which is provided with means for operating a meter at the calling station a plurality of times when the called subscriber answers according to the number of exchanges through which the call progressed, and a timing device for repeating the initial charge at predetermined intervals.
17. In a telephone system which is arranged to require an assessment of a certain charge for each zone through which a call progresses and in which means are provided for extending calls through a plurality of intervening zones to a called line, means for assessing a charge on the calling subscriber in accordance with the number of zones through which the call progressed, and a timing device for repeating said charge at predetermined intervals.
18. In a telephone system, a calling line, means for establishing connections from said line to called lines over a series of successive link circuits requiring different toll charges, a meter for the calling line, a meter operating device for controlling said meter, said device adjusted during the progress of the call a certain number of times as each link circuit is added to the connection, said device controlled by the response of the called subscriber to operate the meter a predetermined number of times for each time interval of conversation in accordance with its adjustment.
19. In a telephone system, a line, a meter therefor, an automatic switch accessible to said line, a meter controlling device individual to said switch, a trunk circuit accessible to said switch for use by the calling subscriber for extending connections from said line to called lines requiring varying toll charges, said device adjusted during the extension of the call over said trunk line in accordance with the proper charge and controlled by the response of the called subscriber to operate said meter in accordance with the adjustment a plurality of times for each interval of conversation.
20. In a telephone system, in which there are zones of calling arbitrarily established and a meter on each line adapted to be operated a variable number of times depending upon the number of zones through which a call has progressed when the called subscriber answers, means in each zone through which a call is successively extended for operating the meter one or a plurality of times in accordance with the charge for each zone the accumulative charge for all the zones through which the call progresses comprising the complete charge for the call, and means for repeating said initial charge at regular intervals during conversation.

Signed by me at Chicago, Cook county, State of Illinois, this 23rd day of July, 1917.

WILLIAM WALTER OWEN.
